EX

DESIGN.

G. WILKINSON.

HANDLE OF SPOONS, FORKS, &c.

No. 15,644.

Patented Dec. 23, 1884.

UNITED STATES PATENT OFFICE.

GEORGE WILKINSON, OF PROVIDENCE, RHODE ISLAND, ASSIGNOR TO THE
GORHAM MANUFACTURING COMPANY, OF SAME PLACE.

DESIGN FOR A HANDLE OF SPOONS, FORKS, &c.

SPECIFICATION forming part of Design No. 15,644, dated December 23, 1884.

Application filed September 11, 1884. Term of patent 7 years.

To all whom it may concern:

Be it known that I, GEORGE WILKINSON, of the city and county of Providence, and State of Rhode Island, have invented a new and original Design for the Handles of Spoons, Forks, &c.; and I do hereby declare the following specification, taken in connection with the accompanying photographic illustration, forming a part of the same, to be a description thereof.

This design relates to the handles of table-ware, such as spoons, forks, ladles, knives, &c.

In the accompanying photograph, Figure 1 represents the front or face of a spoon, and Fig. 2 the back of a fork, the handles of which bear the design. The sides *a a* of the handle diverge upwardly, so that the handle gradually increases in width from its lower end. The edges of the upper portion of the handle are convex at *b b* and *c c*, and are joined by a convex head or end, *d*. The front face of the handle is divided by a transverse band, *e*, into two parts, the lower of which has longitudinal corrugations *f*. The upper part, *g*, is ornamented by panels *h h*, having divergent beads, by scrolls *i i*, above said panels, and by a fan-shape ornament, *j*, which surmounts said scrolls. The back or rear face of the handle

has ornamental panels *l l*, and a fan-shape ornament, *m*, surmounting said panels.

What I claim, and desire to secure by Letters Patent, is—

1. The design for the handles of spoons, forks, &c., consisting of a handle gradually increasing in width from its lower end upwardly, and having its edges convex at *b b* and *c c*, and a convex head or end, *d*, and its face provided with an ornamental transverse band, *e*, longitudinal corrugations *f* below said band, panels *h h*, having divergent beads, scrolls *i i*, and fan-shape ornament *j*, substantially as described and shown.

2. The design for the handles of spoons, forks, &c., consisting of a handle having its sides divergent upwardly and convex at *b b* and *c c*, and a convex head or end, *d*, and one of its faces provided with an ornamental transverse band, *e*, ornamental panels *h h*, scrolls *i i*, and fan-shape ornament *j*, and the other face provided with ornamental panels *l l* and fan-shape ornament *m*, substantially as described and shown.

GEORGE WILKINSON.
